(57) **CLAIM**

The ornamental design for a adapter for virtual reality hand controller, as shown and described.

DESCRIPTION

FIG. 1 is a perspective view showing the new adapter for virtual reality hand controller;

FIG. 2 is a top side view thereof;

FIG. 3 is a bottom view thereof;

FIG. 4 is a front view thereof;

FIG. 5 is a back view thereof;

FIG. 6 is a right side view thereof;

FIG. 7 is a left side view thereof; and,

FIG. 8 is a perspective view showing the adapter for virtual reality hand controller in use when attached to an example of a virtual reality controller.

FIGS. 1-8 depict a first embodiment of an adapter for virtual reality hand controller for a right hand. A second embodiment for a left hand is a mirror image of the first embodiment shown in FIGS. 1-8.

The broken lines shown in FIGS. 1-7 illustrate portions of the adapter for virtual reality hand controller that form no part of the claimed design; the broken lines in FIG. 8 illustrate an environmental structure that forms no part of the claim thereof.
